METHOD AND APPARATUS FOR LOWERING THE CHLORATE CONTENT OF ALKALI METAL HYDROXIDES

Sidney G. Osborne, Saint Davids, Ontario, Canada, assignor to Hooker Electrochemical Company, Niagara Falls, N. Y., a corporation of New York

No Drawing. Application January 13, 1954
Serial No. 403,923

9 Claims. (Cl. 204—98)

This invention relates to methods and apparatus for reducing the amount of chlorates in caustic solutions produced by electrolysis in ordinary diaphragm type cells.

In the electrolytic cells of the diaphragm type, such as the type of cell described in United States Patent 1,866,065, the anode compartment is separated from the cathode compartment by a permeable diaphragm. Alkali metal chloride brine, such as lithium, sodium, or potassium chloride, is introduced into the anode compartment, where it comes into contact with the anodes, and is caused to percolate through the diaphragm into the cathode compartment, where it comes into contact with the cathodes. When an electric current is passed between these electrodes, chlorine is liberated at the anodes and alkali metal hydroxide is formed at the cathodes with the liberation of hydrogen. In order to minimize voltage drop in the cell, the cathodes are placed as close to the diaphragm as possible; and in fact, in practice the diaphragm is generally a thin sheet of fibrous material, preferably of asbestos, overlying and supported by cathodes of woven iron wire screen. The cathode compartment may be occupied by hydrogen, but in best modern practice it is allowed to fill up with caustic alkali solution to a level at which the diaphragm is largely submerged, and to overflow from the cell at that level. In any case, the surface of the cathodes in contact with the diaphragm is wet with catholyte.

A review of the electrochemistry of deposited diaphragm type cells has been given by Murray, R. L., and Kircher, M. S. in the Transactions of the Electrochemical Society; vol. 86, pp. 83—106; 1944.

Chlorine, as such and as hypochlorous acid, is more or less soluble in brine, even at elevated temperatures, and forms hypochlorites in accordance with the following representative equations:

Thus, some chlorine inevitably passes through the diaphragm in solution in the percolating brine. When coming into contact with the caustic alkali in the cathode compartment, this chlorine reacts with the alkali to form alkali metal hypochlorite, in accordance with the following representative equations:

This, of course, represents a loss of both chlorine and caustic alkali as useful product; hence a loss in current efficiency.

A more serious loss comes about through back migration from the cathode compartment of the cell, or face of the cathode itself, through the diaphragm to the anode compartment, chiefly of negatively charged hydroxyl ions seeking their way to the positive anode. Hydroxyl ions reaching the anodes as such are then discharged, liberating oxygen. However, at normal anolyte pH, which is

2

about 4, hypochlorous acid may be formed by reaction with the chlorine in accordance with the following equation:

Furthermore, since the hydroxyl ions carry a negative charge, which is discharged at the anode, their back migration represents a loss in current efficiency.

Hypochlorite ion, which is formed from the hydrolysis of chlorine dissolved in the anolyte, is discharged at the anode to form chlorate ion in a manner after the following equation:

Further, hypochlorous acid and hypochlorite ion are unstable under the conditions of electrolysis and tend to form chlorate ion and oxygen according to the following equations:

The oxygen produced from hydroxyl ions discharging at the anode and from the decomposition of some of the hypochlorites in the anolyte thereby results in contamination of the chlorine; also, since the anodes are of graphite, some of the oxygen attacks the anodes, slowly consuming them, which results in the contamination of the chlorine with carbon dioxide. Similarly, the oxygen produced from the decomposition of some of the hypochlorites in the catholyte results in contamination of the hydrogen with oxygen.

In the cathode compartment substantial amounts of the hypochlorite and chlorate ions are reduced by nascent hydrogen (H^0) formed at the cathode according to the following equations:

However, some of the hypochlorite and chlorate ions escape reduction in the catholyte and pass out of the cell and thereby contaminate the cell effluent which is mainly spent brine having the alkali metal hydroxide dissolved therein.

In the presence of an excess of alkali, the chlorate is quite stable. It therefore tends to persist in the cell effluent and to pass on through to the evaporators in which the caustic alkali is concentrated. Practically all of the chlorate survives the evaporation and remains in the final product, where it constitutes a highly objectionable contaminant, especially to the Rayon industry.

The problem of lowering chlorates has been attacked at two main points:

(a) The chlorates having been formed, can be reduced in the further processing of the caustic alkali and by special treating methods. See for instance, U. S. Patents 2,622,009; 2,044,888; 2,142,670; 2,207,595; 2,258,545; 2,403,789; 2,415,798; 2,446,868; and 2,562,169; and British patents 642,946 and 664,023 which show representative examples of different methods used for reducing the chlorates after they have been formed.

(b) The production of chlorates during the electrolysis can be lowered by adding a reagent to the brine feed which reacts preferentially with the back-migrating hydroxyl ions from the cathode compartment of the cell making their way through the diaphragm into the anode compartment, and by such a reaction prevents the formation of some of the hypochlorites in the manner shown by Equation 6 and thus additionally preventing these hypochlorites from further reacting to form chlorates in the manner shown by Equations 7, 8, and 9. Reagents such as hydrochloric acid shown in U. S. Patent 583,330, and sulfur in an oxidizable form, such as sodium tetrathionate, shown in

U. S. Patent 2,569,329 are illustrative of methods which have been used to attack the problem of chlorates in caustic by removing the back migrating hydroxyl ions before they can react to form chlorates.

It is an object of this invention to provide a new point of attack for the lowering of chlorates in caustic alkali solutions produced in cells of the diaphragm type. Another object is to provide a method for the prevention of chlorate formation during the electrolytic decomposition of alkali metal chlorides in diaphragm type cells wherein the hypochlorites are reduced before they can form chlorates. A third object of this invention is to provide a method for the prevention of the formation of chlorates during the electrolysis of alkali metal chlorides which is economical to adapt into the electrolysis process and does not introduce into the cell effluent any undesirable impurities. A fourth object of this invention is to provide an improved diaphragm for the electrolysis of alkali metal chlorides. A fifth object is to provide a method for preventing the formation of chlorates during the electrolysis of alkali metal chlorides in cells of the diaphragm type, which method can be used in conjunction with other known methods for lowering chlorates to give an improved result therewith, and without any harmful effects therewith.

I have discovered that the problem of lowering chlorates can be attacked at another point. My discovery is that production of chlorates during electrolysis of alkali metal chlorides in diaphragm type cells can be prevented by attacking the overall reaction at the point of hypochlorite formation, that is, destroying the hypochlorite before it can react to form chlorate.

I have now found that if small amounts of a finely divided material selected from the group consisting of nickel, cobalt, their brine soluble salts, their hydroxides and mixtures thereof are dispersed into the diaphragm, and the resulting diaphragm containing the finely divided compounds used in the electrolysis of alkali metal chlorides, the chlorate content of the resultant cell effluent can be lowered substantially from what the chlorate content would have been had such a compound not been added; likewise, the chlorate content of the alkali metal hydroxide produced therefrom is proportionately lowered.

Although I do not wish to be limited to any theory, I believe the reduction of the hypochlorites might be effected in a manner after the following illustrative equations:

The reduction of the hypochlorites might also be effected in a manner after Equation 10 above to a greater extent than if the finely divided compound of my invention had not been added to the diaphragm.

The compounds to be used in this invention are powdered or otherwise finely divided nickel and cobalt, and their brine soluble salts of nickel and cobalt which upon exposure to dilute caustic solutions such as are found in diaphragm cells during the electrolysis of alkali metal chlorides, react to form insoluble hydroxide salts of nickel and cobalt and are thereby retained in the diaphragm and not dissolved away during continuous use of the diaphragm in the electrolysis of alkali metal chlorides. Mixtures of nickel, cobalt, their brine soluble salts and their hydroxides thereof may also be used herein. For instance, during electrolysis the catalytic materials dispersed into the diaphragm may be both finely divided nickel and finely divided hydroxides of nickel; or, the materials may be powdered cobalt and finely divided hydroxides of cobalt; or they may be powdered nickel and cobalt; or, they may be powdered nickel and powdered cobalt and the finely divided hydroxides of nickel and cobalt; or, the catalytic material may be the finely divided

hydroxides of nickel and cobalt. I prefer to use nickel in a finely divided state, such as powdered nickel commonly available in saleable form, or a soluble salt of nickel such as a chloride of nickel which is also commonly available. However, finely divided cobalt and soluble salts thereof such as cobalt chloride, are also satisfactory. Other brine soluble salts of nickel and cobalt or mixtures thereof which may be used to disperse the catalyst into the diaphragm are their acetates, ammonium chlorides, ammonium sulfates, ammonium nitrates, bromides, ammonium bromides, chlorates, fluorides, formates, hypophosphite, iodides, nitrates, perchlorates, sulfates and others. The particular brine soluble salt used is not important, because the catalyst is converted over into an insoluble hydroxide form during electrolysis.

The amount of catalyst to be dispersed into the diaphragm may be varied within wide ranges without departing from the scope of this invention. In general, a catalytic amount is all that is necessary. I have found that catalyst concentrations in the diaphragm as low as 0.5 percent by weight and as high as 10 percent by weight of the diaphragm are effective. Concentrations as low as 0.25 percent and as high as 20 percent may also be used, but catalyst concentrations above 20 percent are not necessary and may be uneconomical to use. I prefer to use a catalyst concentration of between one percent and 5 percent by weight of the diaphragm.

The diaphragms of this invention may be fabricated by employing permeable diaphragm material in any of the usual forms. Asbestos is the most commonly used material for preparing permeable diaphragms and any of the commercially available forms may be used, such as asbestos paper, asbestos cloth, finely divided asbestos and other forms of asbestos may all be included within the scope of this invention as being adaptable to fabricating the improved diaphragms of this invention. If required, a suitable diaphragm supporting material, such as the steel cathode screen, may also be employed to fabricate the diaphragms of this invention.

The diaphragms may be fabricated by incorporating the catalyst in the diaphragms in several ways without departing from the scope of this invention. The compound may be dispersed into the slurry before being deposited on the steel screen, or it may be dispersed into the diaphragm after the diaphragm has been deposited on the screen. The end result is to provide an improved deposited diaphragm having dispersed thereon a minor amount of catalyst which promotes the reduction of the hypochlorites as they come into association therewith. Similarly, the catalysts may be dispersed into other types of diaphragms, such as asbestos paper and asbestos cloth type diaphragms, by dispersing minor amounts of the materials into finely divided or porous materials. For example, where possible I prefer to disperse the catalytic material into the diaphragm while the diaphragm is being fabricated, in order to obtain a more uniform distribution of catalyst throughout the porous surfaces of the resulting improved diaphragm.

After fabricating the improved diaphragms of this invention and while under the influence of the electrochemical conditions existing within diaphragm type cells during the electrolysis of alkali metal chlorides, the brine soluble salts of cobalt and nickel are converted over to a brine insoluble hydroxide form. Thus, during electrolysis the improved diaphragms of this invention have dispersed therein a catalytic amount of a material selected from the group consisting of nickel, cobalt, their hydroxides, their brine soluble salts, and mixtures thereof.

My invention is more fully described by the following examples but I do not wish to be limited thereto except as defined in the appended claims.

EXAMPLE I

Part I

75 A deposited diaphragm was fabricated by pouring a

slurry of asbestos suspended in brine through a steel screen of the type used as cathodes in cells for the electrolysis of alkali metal chlorides. After most of the brine had drained through the screen, the mat of asbestos remaining on the screen was drawn down onto the screen more firmly by means of a mild vacuum being placed on the back side of the screen. This deposited diaphragm was assembled into a horizontal cell, constructed essentially of a steam-heated Büchner funnel into which was placed the steel cathode screen having the asbestos diaphragm deposited thereon and above the diaphragm was suspended a horizontal type graphite anode. Brine was fed in from the anode side and the cell brought to about 84 degrees centigrade by passing steam into the jacket of the Büchner funnel, electrical connections were made between the graphite anode and steel cathode screen, and the current turned on and regulated to about 8.0 amperes. The cell was operated in this manner with the brine feeding into the anode compartment and exiting from the cathode compartment out of the bottom of the Büchner funnel at the rate of about 1.7 cubic centimeters of flow per minute for a period of about two hours at which time it was observed that equilibrium operating conditions had been reached. The sample of cell effluent taken at this time analyzed 144 grams per liter of sodium hydroxide and 1.89 grams of sodium chlorate per 1000 grams of sodium hydroxide.

Part 2

A second deposited diaphragm was fabricated as in Example I, Part 1, above, except that the slurry of asbestos suspended in brine also contained nickel powder in an amount such that the asbestos deposited on the steel screen contained 10 percent by weight nickel dispersed therein. The diaphragm thus formed was placed in the same cell of Example I, Part 1, and operated in substantially the same manner. The sample of the cell effluent taken after equilibrium operating conditions had been reached, analyzed 148 grams per liter of sodium hydroxide and 0.17 gram of sodium chlorate per 1000 grams of sodium hydroxide.

A comparison of the results of Part 1 with the results of Part 2 of this example shows that the chlorate content of the cell effluent was reduced 91 percent by dispersing 10 percent powdered nickel into the deposited diaphragm of the cell.

EXAMPLE II

The following table gives the results obtained in the operation of commercial cells of the type illustrated in U. S. Patent No. 1,866,065, with brine saturated at 60 degrees centigrade and containing about 310 grams of sodium chloride per liter and into the deposited diaphragms of which have been dispersed varying amounts of powdered nickel. The percentages of nickel given are based on the combined dry weight of asbestos and nickel deposited. The chlorate contents are the averages of several months operation in each of the individual cells identified.

Cell	Catalyst Concentration in the Diaphragm, Percent	Average Chlorate Content of the Cell Effluent, lbs. NaClO ₃ /1,000 lbs. NaOH
Plant Average.....	None	0.9-1.0
A.....	10	0.57
B.....	5	0.55
C.....	2.5	0.47
D.....	1.25	0.70

No harmful or abnormal effects were observed during the period that each of the above cells was run.

I have also found that my method for preventing

chlorate formation during the electrolysis of alkali metal chlorides in deposited diaphragm type cells can be used in conjunction with other known methods for reducing chlorates during electrolysis such as the method given in U. S. Patent 2,569,329, which includes adding a reagent to the brine feed which reacts preferentially with the back migrating hydroxyl ions, and that no harmful effects are found due to this joint process. Further, I have found that these two methods have an additive effect on the actual overall reduction in chlorate content of the cell effluent. These findings are illustrated in Example III.

EXAMPLE III

A commercial cell of the type illustrated in U. S. Patent No. 1,866,065 having a deposited diaphragm in which was dispersed therein finely divided nickel chloride in the amount of 2.4 percent by weight was operated in the same manner as those cells shown in Example II except that the brine feed contained 0.03 weight percent sodium tetrrosulfide. The average chlorate content over a period of several months' operations was 0.28 pound of sodium chlorate per 1000 pounds of sodium hydroxide. No harmful or unusual effects were observed during this period.

Thus in a manner after Example III the method of this invention may be used in conjunction with the prior art methods of adding an acid reagent such as hydrochloric acid or a reagent of the type described in U. S. Patent No. 2,569,329, that is, a sulfur compound in an oxidizable state, to the brine feed to help lower the chlorate formation even more than it would have been lowered had my method not been used with one of these known methods.

I claim:

1. In the method of decomposing alkali metal chlorides in electrolytic alkali chlorine cells of the diaphragm type, the improvement which comprises effecting said electrolysis in the presence of a finely divided catalytic material selected from the group consisting of nickel, cobalt, their hydroxides and mixtures thereof dispersed in said diaphragm wherein said finely divided material dispersed in the diaphragm is between about 0.25 percent and about 10 percent by weight of the diaphragm.
2. The method of claim 1 wherein the amount of material dispersed in the diaphragm is between about 1.0 percent and about 5.0 percent by weight of the diaphragm.
3. The method of claim 1 wherein the material is powdered nickel.
4. The method of claim 1 wherein the material is an hydroxide of nickel.
5. In a method for decomposing sodium chloride brine in electrolytic alkali chlorine cells of the diaphragm type, the improvement which comprises: effecting said electrolysis in the presence of a finely divided hydroxide of nickel dispersed in said diaphragm in an amount between about 0.5 percent and 10 percent by weight of the diaphragm.
6. A diaphragm for use in electrolytic cells for the electrolytic decomposition of alkali metal chlorides comprising a permeable asbestos diaphragm having dispersed in finely divided form therein a catalytic material selected from the group consisting of nickel, cobalt, their hydroxides and mixtures thereof wherein said finely divided material dispersed in the diaphragm is between about 0.25 percent and about 10 percent by weight of the diaphragm.
7. A diaphragm according to claim 6 wherein the asbestos is deposited on a steel screen.
8. The diaphragm of claim 7 wherein the catalytic material is powdered nickel.
9. The diaphragm of claim 7 wherein the catalytic material is an hydroxide of nickel.
